His Attorney.

UNITED STATES PATENT OFFICE

EDWARD M. HEWLETT, OF SCHENECTADY, NEW YORK, ASSIGNOR TO GENERAL ELECTRIC COMPANY, A CORPORATION OF NEW YORK

PROTECTIVE ARRANGEMENT

Application filed June 28, 1929. Serial No. 374,481.

My invention relates to improvement in protective arrangements for electric circuits and more particularly such as embody fusible elements for effecting a circuit interruption on the occurrence of abnormal circuit conditions.

Where fuses, particularly of the expulsion type, are chosen so as to be relatively sensitive, the fuse is apt to run at a temperature destructive to the fuse holder. Moreover, in case of relatively high voltages, as in the protection of potential transformers for instruments, meters, relays, etc., the current may be so small as to require a fusible element of such a small cross-section as to be mechanically weak and inconvenient to handle. Furthermore, with such a small cross-section, the aging or deterioration of the fusible element may result in a circuit interruption under normal conditions. If the cross-section is increased, then the sensitivity is destroyed and the expulsion effect may be lost since the fuse, instead of melting throughout its length substantially instantaneously, may merely break at the weakest point and gradually melt. In this case a destructive arc is maintained, the circuit is not interrupted and damage results to the fuse holder and probably other apparatus. In view of these difficulties, an object of my invention is to provide an improved protective arrangement for amplifying the fusing effect only on the occurrence of abnormal circuit conditions whereby a mechanically and electrically strong fuse may be used without sacrificing the safety or sensitivity of the protection desired.

My invention will be better understood from the following description when considered in connection with the accompanying drawings and its scope will be pointed out in the appended claims.

In the accompanying drawings Fig. 1 illustrates, partly diagrammatically an embodiment of my invention and Fig. 2 illustrates diagrammatically a modification of a part of the embodiment of my invention shown in Fig. 1.

In the embodiment of my invention shown in Fig. 1, an electric circuit 4, which may be energized from a bus or feeder 5, includes a

winding of a potential transformer 6 and is arranged to be controlled by a fuse 7 in accordance with my invention by means of which the current in the fusible element 8 is suitably amplified on the occurrence of abnormal conditions, for example on the circuit 4 or on the transformer 6 or a circuit 9 supplied thereby.

As shown, the fuse 7 includes a shell or tube 10 of insulating material and a cap 11, which may be of conducting material, suitably secured thereto. The cap 11 serves as a housing for the fusible element 8, one end of which is suitably insulated from the cap by means such as insulating blocks 12 and 13. Between these are mounted conducting members, such as disks 14 which may be centered in recesses in the blocks 12 and 13 so as not to touch the cap 12. To hold the fusible element 8 in place so as to be easily replaceable, a screw plug 15 may be employed to clamp the bearing plate 16, the blocks 12 and 13, and the disks 14 tightly against each other and the base of the cap 11. Within the tube 10 is mounted a conducting element 17 connected in the circuit 4 to be protected and at one end to an intermediate point of the fusible element 8. The conducting element 17 may also be a fusible element thus providing two fusible portions for the fuse. In order to assist in separating the fusible elements upon rupture, a spring 18 may be connected to the base of the tube and to a point on the conducting element 17.

In order to amplify the current supplied to the fusible element 8 on the occurrence of abnormal circuit conditions, I provide in accordance with my invention transforming means 19 which, as shown, is arranged to supply to the fusible element 8 on the occurrence of current in excess of a predetermined value in the circuit 4, a current dependent on and greater than the current in this circuit. For this purpose the magnetic circuit of the transforming means is arranged normally to have a high reluctance so that the coupling between the primary and secondary windings 20 and 21 is normally relatively weak but the reluctance is arranged to be substantially decreased when a faulty circuit condition occurs.

5 curs. As shown this change in reluctance is accomplished by providing within the magnetic structure 22 and in the magnetic circuit of the windings 20, 21, an air gap under the control of a movable member such as a magnetic member or armature 23, subject to the control of the winding 20. The position of this armature relatively to the winding 20, that is the pick-up point or predetermined 10 current at which the decrease in reluctance is effected may be varied by any suitable adjusting means, shown as a screw 24 mounted in a supporting bracket 25.

15 In order to obtain the desired amplifying effect responsive to conditions in the circuit 4, the primary winding 20 may be connected in series relation with this circuit and to an intermediate point of the secondary winding 21 such as the electrical center or middle 20 thereof, while the fusible element is connected across the secondary winding through the cap 11, the disks 14, the plate 16 and the plug 15 through the conductors 26, one of which passes through an insulator 27 in the cap 25. 11. In this way the current in the circuit 4 flows in parallel through the two halves of the secondary winding 21 and the resultant magnetic effect is substantially zero. Due to the normally weak inductive coupling between the windings 20, 21 practically little, if any, current appears in the parts of the fusible element 8 on either side of the conducting element or lead 17 in excess of one-half of the current in the circuit 4.

30 35 On the occurrence of abnormal circuit conditions causing a current in the circuit 4 sufficient to pick up the armature 23, the reluctance of the magnetic circuit of the windings is so decreased that their resulting 40 strong inductive coupling produces a surge of current in the winding 21. This current is superimposed on the circuit current already flowing in the fusible element 8 which consequently melts and releases the conducting element 17 which under the force of the 45 spring 18 is quickly expelled from the tube. If the element 17 is also of fusible material, it may also melt on the occurrence of a sufficiently large current and thus expedite the 50 expelling action and more quickly effect the arc interruption.

Inasmuch as the current supplied to the fusible element may be amplified to any desired degree on the occurrence of faulty conditions, the fusible element 8 may be of large cross-section for mechanical strength without destructive heating under normal operation. This is likewise true of the element 17, if of fusible material, since it is relied upon 55 only for fault currents sufficiently great, without amplification, to cause its rupture.

60 Instead of using a transforming means 22 with the windings arranged as in Fig. 1, an auto-transformer may be used as shown in 65 Fig. 2. In this case also the primary wind-

ing is in the circuit to be protected and the secondary winding supplies the fusible element 8.

While I have shown and described my invention in considerable detail, I do not wish to be limited to the exact arrangements shown, but seek to cover in the appended claims all those modifications that fall within the true spirit and scope of my invention.

What I claim as new and desire to secure by Letters Patent of the United States, is:

1. In combination, an electric circuit, a fusible element connected in said circuit, transforming means for supplying to said fusible element on the occurrence of abnormal circuit conditions a current dependent on and greater than the current in said circuit including a normally high reluctance magnetic circuit, a winding connected in said electric circuit and a cooperating winding connected to supply said fusible element, and means for decreasing the reluctance of the magnetic circuit of said transforming means on the occurrence of abnormal circuit conditions.

2. In combination, an electric circuit, a fuse in said circuit, a transformer for supplying to said fuse on the occurrence of abnormal circuit conditions a current dependent on and greater than the current of said circuit including a normally high reluctance magnetic circuit, a primary winding connected in series in said electric circuit and a secondary winding having its electrical center connected to one terminal of said primary winding, said fuse being connected across said secondary winding, a circuit lead from said fuse, and means for substantially decreasing the reluctance of the magnetic circuit of said transformer on the occurrence of current in said circuit in excess of a predetermined value.

3. In combination, an electric circuit, a fuse directly connected in said circuit, a transformer for supplying to said fuse on the occurrence of abnormal circuit conditions a current dependent on and greater than the current in said circuit including a primary winding connected in series relation with said circuit, a secondary winding connected to supply said fuse and a magnetic structure including a movable magnetic member arranged normally to be positioned to provide a relatively large air gap in the magnetic circuit of said windings and operative on the occurrence of current in excess of a predetermined value in said primary winding substantially to decrease said air gap.

4. In combination, an electric circuit, a fuse directly connected in said circuit, a transformer for supplying to said fuse on the occurrence of abnormal circuit conditions a current dependent on and greater than the current in said circuit including a primary

winding connected in series relation with said circuit, a secondary winding connected to supply said fuse and a magnetic structure including an armature arranged normally to provide a relatively large air gap in the magnetic circuit of said windings and operative on the occurrence of current in excess of a predetermined value in said circuit substantially to decrease said air gap.

circuit lead from said fuse, and means for increasing the inductive coupling of said transformer windings on the occurrence of abnormal circuit conditions.

In witness whereof, I have hereunto set my ⁷⁰
hand this 27th day of June, 1929.

EDWARD M. HEWLETT.

10 5. In combination, an electric circuit, a fuse including two portions, one connected in series in said circuit and to an intermediate point of the other portion, transforming means for supplying to said other fuse portion

15 on the occurrence of abnormal circuit conditions a current dependent on and greater than the current in said circuit including a secondary winding connected across said other fuse portion, a primary winding connected in series relation with said circuit and to said secondary winding and a normally high reluctance magnetic structure for said windings, and means for substantially decreasing the reluctance of said structure on the occurrence of abnormal circuit conditions.

6. In combination with a potential transformer, a fuse connected in circuit with a winding of said transformer, transforming means for supplying to said fuse on the occurrence of abnormal conditions on said potential transformer a current dependent on and greater than the current in said potential transformer winding including a primary winding connected in series relation with the potential transformer winding, a secondary winding connected to supply the fuse and a normally low reluctance magnetic circuit for said primary and secondary windings, and means for decreasing the reluctance of said magnetic circuit on the occurrence of current in excess of a predetermined value in said potential transformer winding.

100

7. In combination, an electric circuit, a fusible element connected in said circuit, transforming means for supplying to said fusible element on the occurrence of abnormal circuit conditions a current dependent on and greater than the current in said circuit, including a winding connected in said circuit and a cooperating winding connected to supply said fusible element, said windings being normally loosely inductively coupled and means for increasing the inductive coupling of said windings on the occurrence of abnormal circuit conditions.

105

8. A protective arrangement for an electric circuit including a transformer having its primary winding connected in series in the circuit, one terminal of said primary winding being connected to the electrical center of the secondary winding of the transformer, said transformer windings being normally, loosely, inductively coupled, a fuse connected across said secondary winding, a
